UNITED STATES PATENT OFFICE.

ERLE H. HAND, OF STAPLETON, NEW YORK.

BALANCE BEAM FOR TONE ARM OF TALKING MACHINES AND THE LIKE.

Application filed July 3, 1922. Serial No. 572,442.

To all whom it may concern:

Be it known that I, ERLE H. HAND, a citizen of the United States, residing at Stapleton, borough of Richmond, State of New York, have invented a new and useful Balance Beam for Tone Arm of Talking Machines and the like, of which the following is a specification.

My invention consists of a novel construction of an articulated tone arm provided with novel counterbalancing devices, the sound passages in the tone arm being straight or rectilinear and means being provided for accurately balancing or positioning the tone arm member carrying the sound box with respect to the main tone arm body and the record being played, whereby the weight of the sound box can be delicately and accurately adjusted with respect to the groove of the record being played, so that substantially a predetermined calculated pressure or contact can be had between the stylus and the sound reproducing groove of the record irrespective of whether the same be of the hill and dale or the laterally undulating type, whereby an improved reproduction of sound will be obtained and the life of the record prolonged.

It further consists of a novel construction of counterbalancing devices and locking devices carried by an articulated tone arm of the general character above referred to.

It further consists of novel means for forming a tight joint or seal between the various coacting elements of my device, whereby all play or lost motion between the parts is dispensed with so that there is no leakage or emission of the reproduced sounds except through the larger end of the tone arm.

It further consists of a novel construction of balance beam, ball bearings therefor and standards provided with pivot points engaging trunnions carried by said balance beam, so that friction is reduced to a minimum and a very effective and quickly adjusted device is produced for the purpose intended.

My invention further consists of a novel attachment for a talking machine tone arm, comprising a connection from the tone arm provided with a pendant member which is adapted to be received in a cup provided with ball bearings and with oppositely ex-

tending trunnions, in conjunction with standards adapted to be secured in fixed position on either side of the tone arm and provided with pivot points, which can be nicely and accurately adjusted with respect to said trunnions, according to requirements.

It further consists of other novel features of construction and advantage, all as will be hereinafter fully set forth.

For the purpose of illustrating my invention, I have shown in the accompanying drawings, a form thereof which is at present preferred by me, since it will give in practice satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a perspective view of an articulated tone arm provided with novel counterbalancing and locking devices, embodying my invention.

Figure 2 represents a section on line 2—2 of Figure 1.

Figure 3 represents a top plan view of the tone arm and its adjuncts seen in Figure 1, certain of the parts being shown in section.

Figure 4 represents a plan view of a side disc or closure seen in Figure 3.

Figure 5 represents a section on line 5—5, Figure 3.

Figure 6 represents on an enlarged scale a longitudinal sectional view showing the articulated joint connection and the devices for taking up play and lost motion.

Figure 7 represents a perspective view of another embodiment of my invention.

Figure 8 represents a section on line 8—8 of Figure 7.

Figure 9 represents a side elevation partly in section of the tone arm seen in Figure 7.

Figure 10 represents an end view of a take-up or lost motion device, embodying my invention, the tone arm carrying the same being shown in transverse section.

Figure 11 represents a side elevation of a tone arm equipped with a balance beam and its adjuncts, embodying my invention.

Figure 12 represents a plan view of Figure 11.

Figure 13 represents a side elevation of

an articulated tone arm having applied thereto the balance beam and its adjuncts seen in Figures 11 and 12.

Figure 14 represents a sectional view on line 14—14 of Figure 12.

Figure 15 represents a perspective view of the ball bearing device seen in Figure 14 in detached position, showing the manner of assembling the same.

10 Similar numerals of reference indicate corresponding parts.

Referring to the drawings,

Referring first to Figures 1 and 3, 1 designates my novel construction of articulated tone arm, the same comprising the enlarged or main body portion 2, which is of tapering or conical form and terminates in the transverse housing 3 in which is mounted the inner or joint member 4 provided 20 with the stepped shoulders 5, whereby a tight joint or seal is effected between said housing and the outer portion of said joint member.

The manner of assembling the parts will 25 be understood from Figure 3, the open end of the transverse housing when the parts are assembled being closed by the disk or plate 6, which has an inner square or polygonal recess 7 which engages a similarly 30 shaped projection 8 on the joint member 4.

These parts are held in assembled position by the screw 9 which passes through the hole 10 and is threaded into the seat 11.

12 designates a counterbalancing device 35 which is composed of the arms 13 and 14 joined by the U-shaped member 15, the terminal 16 of the arm 14 being secured to the disk 6 by the fastening devices 17, while the end portion 18 of the arm 12 is secured 40 to the joint member 4 by the fastening devices 19.

The outer end of the arm 13 carries the housing 20 through which passes the spring 45 pressed pin 21, whose end engages one of the seats 22 in the collar 23 mounted on the straight front portion 24 of the tone arm, which is provided with the elbow 25 to which is attached the sound box 26 carrying the stylus 27 of the usual construction, 50 it being apparent that the sound passages in the members 2 and 24 are straight or rectilinear.

The arms 13 and 14 are provided with the 55 weights or counterbalancing devices 28 and 29, which are held in position by set screws or the like.

It will be apparent that one of the arms 60 as 14 and its weight 29, may be omitted if desired.

The inner end of the tubular portion 24 is provided with the outwardly deflected 65 terminal flange 30 against which is screwed the end of the outer sleeve 31, the inner portion of said sleeve being exteriorly threaded and engaging the internal threads

of the joint member 4 as will be understood from Figures 3 and 6.

The outer portion of the sleeve 31 is enlarged or bell-shaped, as indicated at 32, whereby a pocket or chamber 34 is provided 70 which contains the spring 33, one end of said spring bearing against the collar 23 and the opposite end of said spring bearing against the bottom of the pocket 34 as will be understood from Figures 2 and 3. 75

It will be understood that the front portion of the housing 3 has a cut out portion 35, as will be understood from Figures 1 and 5, whereby the requisite amount of play is permitted to the tubular portion 24 and its adjuncts. 80

In the construction seen in Figure 6, I have shown a novel means employed for preventing play or lost motion between any of the parts, the same comprising the clamp 36, which may be constructed in sections, as seen in detail in Figure 10, said sections comprising the curved members 37 which have the ears 38 through which pass the clamping screws 39, said curved portions 37 carrying the inclined arms 40 through the upper ends of which pass the pins 41 whose inner ends press against the seats 42 at the end of the bell shaped member 32, as will be understood from Figure 6. 90

The pin 41 is contained in a housing 43 carried by the arms 40 which contains the spring 44 whose forward end bears against the transverse pin 45, carried by the pin 41, whereby the inner end of said pin 41 is pressed tightly against the seat 42. 100

In Figure 6, I have shown the curved portions 37 as mounted upon the interposed sleeve 46 against which presses one end of the spring 33 so that it will be seen that all play or lost motion between the parts will be effectively taken up. 105

In the construction seen in Figures 7 and 8, I have shown the rear portion 47 of the tone arm 48, as being in threaded engagement with the joint member 49 which is rotatably mounted in the transverse housing 50, which is cut out as indicated at 51 so as to give the requisite amount of play to said tone arm. 110

The joint member 49 is assembled with respect to the housing 50 in substantially the same manner as already described with respect to Figure 3 and its end portions 52 and 53 have secured thereto the arms 54 and 55, which are connected by the transverse member 56 forming a U-shaped structure, said arms 54 and 55 supporting the counterbalancing devices 57 and 58 respectively, the position of said counterbalances 57 and 58 being assured by means of the set screws 59 or the like. 120

The joint member 49 is provided with a curved wall or cut away portion, as indicated at 60, Figure 8, so that a direct com- 125

munication is had between the tone arm 48 and the passage 61 in the upright member 62.

- The straight tubular member 63 of the tone arm is provided with the outwardly deflected flange 64, against which is screwed the inner end of the exteriorly threaded sleeve 65, the threaded end of the sleeve engaging the interiorly threaded tone arm 48, as will be understood from Figure 9.
- 10 The sleeve 65 terminates in the bell shaped end 66, containing the spring chamber 67 in which the spring 68 is contained, the outer end of said spring bearing against the collar 46 which carries the clamps and their adjuncts 36 of the same construction as already described with respect to Figure 6.

It will be obvious that the construction seen at the left of Figures 7 and 9 effectively prevents any play or lost motion between 20 the parts.

In the construction seen in Figures 11 and 12, I have shown the tone arm 69 as being provided with a clamp composed of the upper member 70 and the lower member 71, which are secured together by a screw 72, said upper member being provided with the hook 73, which is engaged by the link 74, which passes through the eye 75 of the balance beam 76, whose outer end carries the counterbalance 77 which is secured in the desired position by the set screw 78 or the like.

The construction and manner of assembling the balance beam 76 will be understood 35 from Figures 14 and 15, said beam having the hole 79 therethrough, through which passes the bolt 80, said bolt passing first through a washer 81, then through the hole 79, then through the ball guide 82, below 40 which is the cup 83 which contains the balls 84, the lower end of the bolt 80 passing through the washer 85 and being provided with a nut 86 for securing the parts in assembled position.

45 The cup 83 is provided with the oppositely extending trunnions 87, whose ends are engaged by the pivot points 88, which pass through the upper ends of the standards 89, whose lower portions or feet 90 are clamped or otherwise secured to the bottom of the upright 91 of the tone arm 69.

In Figure 13, I have shown the tone arm 92 as being composed of the articulated members 93 and 94, which are movably connected together at the point 95 by any suitable means, as the joint already described.

The portion 94 has two clamping members 96 and 97 attached thereto which are held together by any suitable means, the upper member 96 having the hook 98, which is engaged by the lower end of the link 99 whose upper end engages the eye 100 of the balance beam 101.

65 The beam 101 at the point 102 is provided with a ball bearing device, conforming to the

structure seen in Figures 14 and 15 already described and the rear end of said beam is provided with a counterbalance 103 which is held in any suitable position therein by a set screw or the like.

The trunnions of the balance beam 101 seen in Figure 13, are supported by the pivot points 88 carried by the brackets 104, which are mounted upon the upper member 105 of the clamping device which is composed of 70 said upper member and the bottom member 106, secured together by the screws 107. The sound box 108 seen in Figures 11 and 12 is adapted to play any character of record.

Having thus described my invention, what 80 I claim as new and desire to secure by Letters Patent is:—

1. An articulated straight tone arm having one portion cylindrical and the other conical, a tone arm joint intermediate said portions, a collar engaging said cylindrical portion and having seats therein, a spring-pressed pin engaging one of said seats, and an arm having a portion secured to an element of the tone arm joint, one end of said arm carrying said spring-pressed pin and the other end of said arm carrying an adjustable counterbalancing device.

2. In a device of the character stated, an articulated tone arm composed of a conical portion having a transverse cylindrical housing formed thereon, a joint member secured in said transverse housing, and a cylindrical portion engaging said joint member, a collar secured to said cylindrical portion and provided with seats, a spring-pressed pin engaging said seats, an arm attached to the joint member contained within said housing, and an adjustable counterbalancing device carried by said arm, said housing having an opening in its forward portion for permitting the oscillation of said cylindrical portion of the tone arm.

3. In a device of the character stated, an articulated tone arm, composed of a conical portion terminating in a transverse cylindrical housing, a joint member carried by said housing, a cylindrical portion secured to said joint member, a collar having seats thereon carried by said cylindrical member, an arm secured to said joint member, an adjustable counterbalance on said arm, a housing carried by said arm and a spring in said housing having its end adapted to engage in said seats.

4. An articulated straight tone arm having one portion cylindrical and the other conical, a tone arm joint intermediate said portions, a collar engaging said cylindrical portion and having seats therein, a spring-pressed pin engaging said seats, and a counterbalancing device comprising a pair of arms joined by a U-shaped member, said arms having a portion thereof secured to an element of the tone arm joint, each of said 120

arms being provided with weights and one of said arms carrying said spring-pressed pin.

5. An articulated straight tone arm having one portion cylindrical and the other conical, a tone arm joint intermediate said portions, a collar engaging said cylindrical portion and having seats therein, a spring-pressed pin engaging said seats, and a counterbalancing device comprising a pair of

arms joined by a U-shaped member, said arms having a portion thereof secured to an element of the tone arm joint, each of said arms being provided with weights and one of said arms carrying said spring-pressed pin, said element carrying said arms having an opening in its forward portion for permitting the oscillation of said tone arm.

ERLE H. HAND.
